UNITED STATES PATENT OFFICE.

HOMER P. CHANDLER, OF MANSFIELD, OHIO, ASSIGNOR TO THE OHIO BRASS COMPANY, OF MANSFIELD, OHIO, A CORPORATION OF NEW JERSEY.

CONDUCTOR SUPPORT.

Application filed June 12, 1922. Serial No. 567,531.

To all whom it may concern:

Be it known that I, HOMER P. CHANDLER, a citizen of the United States of America, residing at Mansfield, in the county of Richland and State of Ohio, have invented certain new and useful Improvements in Conductor Supports, of which the following is a specification.

My invention relates to a device for supporting electric conductors and has particular reference to a device for suspending a trolley wire from its overhead support.

The object of my invention is to produce a device which is simple, easy of construction and simple in its installation or removal.

My invention resides in the novel construction, combination and relation of the various parts as hereinafter more fully described and set forth.

In the drawing accompanying this specification—

Figure 1 is a side view in elevation of my invention shown as attached to a trolley wire and with a portion broken away to show to better advantage the interior construction.

Fig. 2 is an end view of Fig. 1.

Fig. 3 is a top view of Fig. 1.

Fig. 4 is a sectional view on the line 4—4 of Fig. 1.

Fig. 5 is a sectional view of Fig. 1 on the line 5—5 and also shows the relation of my invention to the overhead support H from which the trolley wire is suspended.

Fig. 6 is a sectional view taken the same as Fig. 5, but showing the relation of parts ready to receive a trolley wire.

In my preferred construction embodying my invention I employ a supporting member 1 provided with a threaded recess to receive a threaded stud of the overhead support or hanger. The lower end of the supporting member 1 is provided with a horizontal pintle 2 secured to the supporting member 1 by means of the neck 3. The outer surface of the member 1 is provided with threads on which is mounted the internally threaded nut 4 provided with the faces 5 for the application of a wrench used in installing my invention upon the trolley wire.

Engaging and suspended by the pintle 2 is a pair of clamping jaws 6—6 provided at their upper end with an arcuate hook 7 for

the purpose of engaging with and suspending the jaws from the pintle. The arcuate member 7 does not entirely surround half the circumference of the pintle 2, but leaves a perceptible space 8 between the upper portions of the members 7—7 to permit the jaws to pivot upon the pintle 3 in the operation of spreading the jaws to receive the trolley wire 9. The lower end of the jaws 6—6 are each provided with a ridge 10 adapted to engage 60 the groove in the trolley wire 9.

To assist in maintaining the jaws 6 in position upon the pintle and to move the jaws into engagement with the trolley wire I employ a casing 11 of elongated formation 70 adapted to slip over the member 1 and engage the shoulder 12 on each jaw. The member 11 is provided with a lip 13 extending substantially the full length thereof to engage the shoulders 12—12. This engagement of the lip 13 with the shoulder 12 throughout the length of the jaw 6 insures a uniform distribution of the force used to close the jaws upon the trolley wire, 75 throughout the length of the jaw. 80

In order to assemble my invention the casing 11 is provided with slots 14 which open into the central recess 15 to allow the pintle 2 and neck 3 to be inserted within the casing. As the casing is open throughout its upper face due to the slots 14 and recess 15 I taper the upper surface of the casing where it engages with the surface of the nut 4 in order that any pressure brought upon the casing by the nut 4 will tend to 90 prevent the casing from spreading. The inner face 16 of the lips 13 are so spaced as to prevent the upper portion of the jaws from spreading to any appreciable extent thereby maintaining them in pivotal engagement with the pintle. 95

To assemble my invention I first insert the pintle portion of the supporting member through the slot 14 and allow the supporting member to drop to its lowest position in which case the pintle will project a sufficient distance below the lips 13 to permit the positioning of the jaws 6 upon the pintle. The jaws 6 are then held in position upon the pintle and the casing 11 allowed to take a position in which the lips 13 engage the shoulder 12 and the nut 4 is then rotated into position either in engagement with the casing 11 or approximately so. The parts are then put in an assembled 105 110

position and it will not be possible to disassemble them unless the nut 4 is removed a sufficient distance away from the casing 11.

To install my invention upon a trolley wire and hanger the nut 4 is first moved outward upon the member 1 by rotation which permits freedom of movement between the nut 4 and the casing 11. The casing 11 is then moved slightly away from the jaws thus permitting the jaws to pivot about the pintle 2 and the lower end to open up sufficiently to receive the trolley wire. Before inserting the trolley wire between the portion 10-10 of the jaws the support as a whole is attached to the overhead hanger H by rotating the whole device and screwing the member 1 upon the stud S until the face of the member 1 engages with the face of the support H. If the jaws are not then in alinement with the trolley wire the device is backed off a sufficient amount to aline the jaws with the trolley wire. The trolley wire is then inserted between the jaws and the nut 4 moved into engagement with the casing 11 by rotating the nut. Further rotation of the nut will force the casing 11 downward and the lips 13 into stronger engagement with the shoulder 12 on the jaws, and the jaws into stronger clamping engagement with the trolley wire. This engagement can be made very secure by the application of a wrench to the nut 4.

There are, of course, modifications which may be made in the disclosure made herein which will fall within the scope of my invention as I have attempted to disclose only my preferred form.

I claim:

1. A conductor supporting device comprising in combination a pair of pivoted clamping jaws, a support for the jaws comprising a boss member having means for attachment to a hanger and an elongated pintle member projecting from opposite sides of the support parallel to the conductor, supporting means on the jaws to engage the pintle member and allow the jaws to pivot thereon and gripping means to clamp the conductor, a clamping member to engage the jaws and move them into engagement with the conductor and having means through which the pintle and boss may be passed and means on the supporting member and movable longitudinally thereof to engage the clamping member to move it into engagement with the jaws.

2. A conductor supporting device comprising in combination a pair of pivotal clamping jaws, a support for the jaws comprising a boss member having means for attachment to a hanger and a pintle member projecting longitudinally of the conductor from the support, supporting means on the jaws to engage the pintle member and allow

the jaws to pivot thereon and gripping means to clamp the conductor, a clamping member to engage the jaws and move them into engagement with the conductor and having means through which the pintle and boss may be passed and means rotatably mounted on the supporting member and movable longitudinally thereof to engage the clamping member to move it into engagement with the jaws.

3. A conductor supporting device comprising in combination a pair of pivoted clamping jaws, a support for the jaws comprising a boss member having means for attachment to a hanger and a pintle member projecting in diametrically opposite directions and parallel to the conductor, supporting means on the jaws to engage the pintle member and allow the jaws to pivot thereon and gripping means to clamp the conductor, a clamping member to engage the jaws and move them into engagement with the conductor and having means through which the pintle and boss may be passed and means having a threaded engagement with the supporting member to move the means into engagement with the clamping member to move the clamping member into engagement with the jaws.

4. A conductor supporting device comprising in combination a pair of clamping jaws to engage the conductor, a clamping member provided with arms to engage and compress the jaws into engagement with the conductor and having a hollow boss between the arms and having slots in the arms opening into the recess in the boss through which a supporting member is passed, a supporting member having a threaded boss to receive a hanger stud and an integrally formed pintle to engage and support the jaws and means to move the clamping member into engagement with the jaws.

5. A conductor supporting device comprising in combination a pair of clamping jaws to engage the conductor, a clamping member provided with arms to engage and compress the jaws into engagement with the conductor and having a hollow boss between the arms and having slots in the arms opening into the recess in the boss through which a supporting member is passed, and a supporting member having a threaded boss to receive a hanger stud and an integrally formed pintle to engage and support the jaws.

6. A conductor supporting device comprising in combination, jaws to engage and grip a conductor, a clamping member to engage the jaws and move them into engagement with the conductor, the clamping member comprising a hollow boss and projections from opposite sides thereof and extending substantially the full length of the jaws and the projections having an open slot connect-

ing with the recess in the boss to receive a supporting member having a pintle secured thereto and having means to engage with an overhead support, means on the jaws to engage

5 gage the pintle and permit pivotal movement relative thereto and means to move the clamping member into engagement with the jaws.

7. A conductor supporting device comprising in combination, a supporting member having means to engage a hanger and a pintle at right angles to the supporting member hanger, jaws to engage and grip a conductor, means on the jaws to engage the 10 pintle and be pivotally supported thereby and each jaw having means to be engaged by a clamping member, a clamping member engaging and supported by said means on the jaws and having a top opening through 15 which the pintle may be passed and means for moving the clamping member into engagement with the jaws.

8. A wire clamp comprising in combination a pair of jaws to engage and grip a wire 20 and having means to pivotally engage a supporting pintle whereby the jaws are supported, a supporting pintle engaged by the jaws as described and having means to secure the pintle to a support or hanger, a 25 clamping member having an opening along one side to receive the jaws throughout their length to move the jaws into engagement with the wire and forming side walls

which engage with the jaws to maintain them in pivotal engagement with the pintle 30 and means for moving the clamping member into engagement with the jaws.

9. A wire clamp comprising in combination a pair of jaws to engage and grip a wire and having means to engage a supporting member and pivot thereon, a supporting member having means to engage a hanger and means having an axis at right angles to the axis of the supporting member, an elongated clamping member having a slot along 40 one edge to receive the jaws and forming parallel edges to engage the jaws substantially their full length and having a slot along the opposite edge through which the supporting member may be passed and 45 means to engage the clamping member to move it into engagement with the jaws.

10. A wire support comprising in combination a pintle extending in the direction of a wire to be gripped, supporting means secured to the pintle to attach the pintle to an overhead support, a pair of oppositely disposed jaws pivotally engaging the pintle and movable into engagement with the wire, a 50 clamping member to engage the jaws to maintain them in pivotal engagement with the pintle and move them into engagement with the wire.

In testimony whereof I affix my signature.

HOMER P. CHANDLER.
